UNITED STATES PATENT OFFICE.

ARTHUR E. SCHULTZ, OF OLNEY, ILLINOIS.

DISPLAY-RACK.

SPECIFICATION forming part of Letters Patent No. 632,065, dated August 29, 1899.

Application filed April 22, 1899. Serial No. 714,143. (No model.)

To all whom it may concern:

Be it known that I, ARTHUR E. SCHULTZ, a citizen of the United States, residing at Olney, in the county of Richland and State of Illinois, 5 have invented certain new and useful Improvements in Display-Racks; and I do declare the following to be a full, clear, and exact description of the invention, such as will enable others skilled in the art to which it applies 10 to make and use the same, reference being had to the accompanying drawings, and to the figures of reference marked thereon, which form a part of this specification.

This invention relates to certain improvements 15 in display devices such as are adapted for use in displaying wares of various kinds for sale; and the object of the invention is to provide a device of this character which shall be of a simple, cheap, and compact construction especially well adapted for holding laces, 20 ribbons and the like, the goods being so held in the device that each pattern or style will be properly displayed and will be readily removable without disturbing the various other 25 patterns displayed in the device.

The invention consists in certain novel features of the construction, combination, and arrangement of the several parts of the improved display device, whereby certain important 30 advantages are attained and the device is made simpler, cheaper, and otherwise better adapted and more convenient for use than various other similar devices heretofore employed, all as will be hereinafter fully set forth.

The novel features of the invention will be carefully defined in the claims.

In the accompanying drawings, which serve to illustrate my invention, Figure 1 is a side 40 elevation showing a device constructed according to my invention, and Fig. 2 is a sectional view taken transversely through the device in the plane indicated by the line 2 2 in Fig. 1. Fig. 3 is a view showing the inner 45 grooved face of one of the side pieces of the device. Fig. 4 is an enlarged fragmentary section taken horizontally through one of the rack-supporting arms of the frame and showing the arrangement of the springs for holding 50 the racks in position on the frame. Fig. 5 is a side view showing an instrument for removing the racks from the device.

As seen in the drawings, the frame of the device is formed of a plurality of similar parallel side pieces 10, there being, as seen herein, three of said side pieces, although it will be obvious that a greater number of these may be employed where more than two series of racks are combined in the device or that only two of the side pieces may be employed 55 where but a single series of racks are provided. The side pieces are held in position and braced at their upper and lower parts by means of transverse braces 11.

The side pieces 10 are each formed with a 60 central body portion 12, from which extends upwardly a series of arms 13, increasing gradually in height from the front to the back of the device, the rearmost arms 14 being provided at their upper ends with the upper 70 brace 11 of the frame. The arms 13 are separated by spaces 15, and the upper ends of said arms are enlarged to form heads 16, in the inner surfaces of which are provided dovetail slots 17 to receive pivot-pins 18, protruding centrally from opposite sides of the racks 19 and having enlarged ends engaged in said slots 17, said racks being in the nature of open rectangular frames, as clearly seen in Fig. 2, the side rails of said racks being extended at their ends to form projections or lugs 20 to hold in place the goods wound on the racks between said projections, as will be readily understood. The enlarged ends of the pivot-pins 18 will, by engagement with the 75 dovetail slots, serve to hold the racks securely in place for movement along said slots.

The slots 17 are provided with curved parts, which, as seen at 21 in Fig. 3, extend above the end portions of said slots in which the 80 pivot-pins 18 are normally seated, and said curved portions form means to hold the pivot-pins normally engaged in their seats at the extremities of the slots. The curved portions 21 also connect with vertical dovetail slots 22, 90 formed in the arms 13 and extending down into communication with dovetail slots 23 in the portions 12 of the side pieces 10, said slots 12 extending rearwardly and converging at the back part of the frame, as shown in Fig. 95 3. At the back part of the frame each slot 23 is formed with an upwardly-extending portion 25, open at the back of the frame to permit the withdrawal of the racks 19 when de- 100

sired and extending at an angle to the main part of said slot 23, so as to form a seat 24, wherein the pivot-pin 18 of the rack 19 is adapted to be held at the back of the device 5 to permit the rack to be rotated in unwinding the goods therefrom, so as to avoid the removal of the racks entirely from the frame in making a sale.

To hold the racks 19 in vertical position, as shown in Fig. 1, springs 26 are employed, secured, as seen in the drawings, to the lower parts of the arms 13, so as to project across the spaces 15 in position to engage the side rails of the racks at their lower parts, as shown 15 in Figs. 1, 2, and 4. The springs 26 are bent at their extremities, as seen at 27, to form stops to prevent forward movement of the lower ends of the racks, and in said springs are also formed bends 28, serving to impede 20 the movement of the racks in the opposite direction, but being sufficiently rounded to permit the racks to ride past them when desired to withdraw the racks from the frame, seats 29 being formed between the bends 27 and 28 25 to receive the edges of the racks 19 when in normal position, as shown in Fig. 4.

For withdrawing the racks from the frame an instrument such as shown in Fig. 5 is preferably employed. This instrument comprises 30 a handle 30, on the end of which is pivoted a part 31, having jaws 32, adapted to be slipped up under the lower edge of the respective racks, the instrument being inserted beneath the racks, as indicated in dotted lines 35 in Fig. 3. A spring 33 connects the pivoted part 31 to the handle 30 and serves to hold said part 31 normally with its jaws 32 upturned, as shown in Fig. 5, but permitting said part to move pivotally in withdrawing the racks. 40 In withdrawing the racks from the frame the instrument is inserted as shown in dotted lines in Fig. 3, and its jaws 32 are applied under the rack to be removed, the upward pressure under the rack serving to lift the same, its pivot-pins 18 passing out of their seats at 45 the ends of slots 17 and up along the upwardly-curved parts 21 of the slots in the arms 13 of the frame. The rack is then lowered, its pivot-pins passing down along the 50 vertical slots 22 in arms 13 and into the slots 23 in the body portions 12 of the side pieces of the frame, the spring connection between the pivoted part 31 and the handle 30 of the instrument serving to permit a certain degree 55 of movement pivotally of the rack in passing under the other racks behind it, as indicated at *x* in Fig. 3. The rack is then drawn rearwardly, and its pivot-pins 18 are seated in the seats 24 at the back part of the 60 frame, as seen at *y* in Fig. 3, so as to hold the rack in position to be rotated to facilitate the removal of the desired length of material therefrom without necessitating the complete withdrawal of the rack from the frame; but 65 when desired—as, for example, when the goods are exhausted from the rack—it may be entirely withdrawn from the frame to per-

mit it to be rewound by simply moving the pivot-pins 18 up the inclined rear ends 25 of the slots 23.

From the above description it will be seen that the improved display device is of an extremely simple and inexpensive construction and is especially well adapted for holding goods to be displayed in windows and showcases, owing to the compact form in which the goods are held and the convenience with which they may be removed, when desired, for making a sale, and it will also be obvious from the above description that the device is 80 capable of some modification without material departure from the principles and spirit of the invention, and for this reason I do not wish to be understood as limiting myself to the precise form and arrangement of the several parts herein set forth.

Having thus described my invention, I claim—

1. In a display device, the combination of a frame having side pieces formed with series 90 of guides each of which is extended downwardly and terminates in a seat, a series of racks having engagement with the respective seats and adapted to be moved along said guides and means for holding said racks in 95 an erect position when engaged with said seats, substantially as set forth.

2. In a display device, the combination of a frame having side pieces formed with series 100 of guides each comprising an upwardly-extending part having a curved end portion the extremity of which is extended downwardly to form a seat, and a series of racks having engagement with the respective seats and adapted to be moved along said guides, sub- 105 substantially as set forth.

3. In a display device, the combination of a frame having side pieces formed with series 110 of guides each comprising a horizontal part and an upwardly-extending part having a 115 seat, and a series of racks having engagement with the respective seats and adapted to be moved along said guides, the upwardly-extending parts of the guides being alined with each other and graduated in height from the front to the back of the frame, substantially as set forth.

4. In a display device, the combination of a frame having side pieces formed with seats, racks having pivot-pins engaging said seats, 120 and guides, the forward ends of which are arranged above and adapted for communication with said seats and which extend downwardly and have their lower ends extended horizontally and along which said racks are 125 adapted to be moved, substantially as set forth.

5. In a display device, the combination of a frame having side pieces formed with series 130 of guides each comprising a horizontal part having a seat at its rear part and an upwardly-extending portion having at its upper part a depending portion formed with a seat at its extremity, and a series of racks having en-

gagement with said guides and adapted to be held in either of said seats, substantially as set forth.

6. In a display device, the combination of 5 a frame having side pieces formed with series of guides each comprising a horizontal portion having a seat at its back part and having beyond said seat an upturned open end, and an upwardly-extending portion having a 10 seat at its upper part, and a series of racks having engagement with said guides and adapted to be held in either of said seats, substantially as set forth.

7. In a display device, the combination of 15 a frame having side pieces formed with series of guides each provided with a seat, a series of racks held in said seats and adapted to be moved along said guides, and elastic means carried by the frame for engaging the racks 20 to hold the same in vertical position, substantially as set forth.

8. In a display device, the combination of 25 a frame having side pieces formed with series of dovetail guides each provided with a seat, and a series of racks having pivot-pins formed with enlarged end portions to fit and slide along said guides, substantially as set forth.

9. In a display device, the combination of a frame having side pieces formed with par-

allel guides each extended downwardly and 30 terminating in a seat at its forward part and also extended downwardly to form a seat at its rear portion, and a rack adapted for movement between the side pieces of the frame and provided with projecting pins at opposite 35 sides to engage and slide along said guides and to engage and turn in said seats, substantially as set forth.

10. In a display device, the combination of 40 a frame having side pieces formed with series of guides each comprising a horizontal portion having a seat at its rear part and an upwardly-extending portion having a seat at its upper part, and a series of racks having engagement with said guides and adapted to be 45 held in either of said seats, the upwardly-extending parts of the guides being alined with each other and being graduated in height from the front to the back of the frame and the horizontal parts of the guides being arranged 50 to converge at the rear part of the frame, substantially as set forth.

In testimony whereof I affix my signature in presence of two witnesses.

ARTHUR E. SCHULTZ.
